UNITED STATES PATENT OFFICE

HUBER H. ROOT, OF MEDINA, OHIO, ASSIGNOR TO THE A. I. ROOT COMPANY, OF MEDINA,
OHIO, A CORPORATION OF OHIO

FOLDING TABLE

Application filed October 8, 1927. Serial No. 224,954.

My invention relates to folding tables and in particular to card tables which as usually made comprise a square or rectangular top with a hinged leg at each of the four corners that may be folded up against the underside of the top when the table is not to be used or opened out to support the table in use. The object of the invention, generally stated, is to provide a table having features of construction which will contribute to diminished cost of manufacture and which will render the table as a finished article better fitted for use.

My invention consists in whatever is described by or is included within the terms or scope of the appended claims.

In the drawing:

Fig. 1 is a perspective view of one of the corner portions of a card table embodying my invention with the legs shown in supporting position;

Fig. 2 is a vertical section thereof;

Fig. 3 is a detail view in perspective of the molded rubber corner.

The table top, 10, includes a light, rectangular frame of strips, 11, of wood, the strips lapping over one another at each corner, and thus presenting at each corner a joint which if exposed does not present a finished appearance, is in danger of being cracked or splintered from bumping against objects, and is apt to scratch or mar or otherwise damage furniture and other surfaces against which the corner may be bumped.

To remedy or overcome these objections and to secure other advantages which will presently be pointed out, there is applied to each corner of the table a corner piece or block, 12, of rubber molded in a permanent angular form to provide two similar wings, 13, at right angles which overlap the corresponding outer surfaces of the strips at the corner and a web, 14, of triangular shape which extends between the wings, 13, at the top and laps over the table top at the corner. The rubber is neither soft nor hard, but of a consistency which will make the corner piece an element of strength or reinforcement at the table corner, and yet serve as a yielding striking

or buffer surface that will cushion knocks or blows received by the table at the corner and administered by the table to articles of furniture or other objects so as to prevent scratching or other injury from the collisions or contacts which are bound to occur in the handling or manipulation of the table. When the table is folded up and stood on edge on the floor the rubber will be in contact with the floor surface and result in sufficient friction to prevent the table slipping on the floor and falling, and, of course, the contact of the rubber with the floor will prevent scratching or injury to the floor surface, these considerations being of particular importance in view of the use of hard wood floors. Contact of the table edge with the floor when placed or leaned against a wall will occur only at the two corners next the floor, the intermediate portion of the wood strip being kept spaced above the floor.

The corner blocks made of rubber besides other advantages over metal used at the corners, possess the advantage that there are no sharp edges or corners which are unavoidable with metal apt to catch into or tear the clothing.

Each corner block or protector can be secured in place by brads or small nails, 15, driven through each wing, 13, two of which suffice.

The table legs, as usual, are each a simple straight stick, 16, of wood pivoted at each corner inside the frame sides, 11. Each leg, 16, has near its end a horizontal hole, 17, by which it is pivotally mounted upon a horizontal rod, 18, which at one end enters a horizontal hole, 19, in a frame side, 11, and at the other end enters a hole in a right angle bracket plate, 20, secured as by screws to the inner side of the adjacent frame side, 11. Between the side of the leg, 16, and the frame side, 11, which has the pivot hole, 19, is a yieldable elastic take-up and pressure-producing device which preferably is a spring, and in particular a coil spring, 21, placed around the portion of the rod, 18, between the leg and the frame side, the thrust of the spring against the leg tending to move the leg towards the bracket, 20, and also to move

the rod, 18, endwise toward said bracket by the provision of a shoulder, 22, on the rod, 18, on the side of the leg opposite that engaged by the spring, 21. To limit the endwise movement of the rod, 18, towards the bracket, 20, the rod, 18, has a shoulder, 23, that engages the ear, 24, at one end of an obliquely extending brace bar, 25, whose other end is pivoted to the leg, 16. The provision of the shoulder, 23, provides a pintle, 26, which enters the pivot hole in the bracket, 20, which is sufficiently short so that endwise movement of the rod, 18, against the pressure of the spring, 21, will permit disengagement of the pintle from the bracket, 20, and thus the ready removal of the leg from the table, should that be desired, for the purpose of replacement or repair.

And the original manufacture or construction of the table is simplified and cheapened by reason of the possibility of endwise movement of the rod, 18, because all of the cooperating parts upon the table and legs may be applied thereto before they are brought together and their assemblage involves merely thrusting the pintle that enters the hole, 19, into the latter compressing the spring, 21, sufficiently to clear the bracket, 20, by the pintle, 26, to place the latter in alignment with the pivot hole in the bracket, 20, and then allowing the rod, 18, to move endwise to place the pintle, 26, in the bracket hole.

Inasmuch as the spring, whether a coil spring, 21, or a flat spring, is an automatically compensating device that takes care of wear which is bound to occur from the frequent swinging of the table legs on their pivots it will be seen that at all times sufficient pressure will be exerted against the leg to keep it tight and snug and prevent lost motion and that looseness of parts which makes the table become rickety and endangers its stability.

It will be observed that the spring besides the other advantages pointed out renders it unnecessary to use any rivets or nuts to hold the parts assembled, which is an advantage not only in dispensing with such parts, and thereby saving the cost, but is also of advantage in making unnecessary the use of tools in assembling the legs and table top, and in the replacement of a leg by a new one.

The diagonal or oblique brace, 25, which extends from the bracket, 20, to the leg with great rigidity and firmness when opened out.

To latch the leg in its opened out position, a latch device, 28, of familiar form is employed.

I claim:

1. A table comprising a top that includes frame bars, independent leg pivoting means comprising a rod passing through a hole in each leg and supported at opposite ends by the frame bars so as to be endwise movable, and an elastic member interposed between the

leg and an adjacent frame bar tending to press the leg away from such frame bar.

2. A table comprising a top that includes frame bars, leg pivoting means comprising a rod passing through a hole in the leg and supported at opposite ends by the frame bars so as to be endwise movable, an elastic member interposed between the leg and an adjacent frame bar tending to press the leg away from such frame bar, and an obliquely extending brace reaching from said leg to the end of said rod remote from the leg.

3. A table comprising a top and independently folding legs, means pivoting each leg to the top including an endwise movable rod that passes through a hole in the leg and which at opposite sides of the leg has a pivotal connection with the top and an elastic member situated adjacent one of such pivotal connections to exert pressure upon each leg and a surface on the top, in the direction of the pivotal axis of the leg.

4. A table comprising a top that includes a frame bar at the edge of the top, said bar having a horizontal perforation, a bracket spaced away from said bar situated beneath the top and having a perforation alining with that in said bar, a rod extending between said bar and said bracket with its ends engaging said perforations and movable axially therein, a leg having a hole through which said rod passes for pivoting the leg thereto, an elastic member interposed between one side of the leg and said bar, the leg being movable along the rod towards said bar and means to limit movement of the legs along the bar in the opposite direction.

5. A table comprising a top that includes a frame bar at the edge of the top, said bar having a horizontal perforation, a bracket spaced away from said bar situated beneath the top and having a perforation alining with that in said bar, a rod extending between said bar and said bracket with its ends engaging said perforations and movable axially therein, a leg having a hole through which said rod passes for pivoting the leg thereto, an elastic member interposed between one side of the leg and said bar, the leg being movable along the rod towards said bar and means to limit movement of the leg along the bar in the opposite direction, and a brace extending between the leg and said rod and said bracket.

6. A table comprising a top that includes a frame bar at the edge of the top, said bar having a horizontal perforation, a bracket spaced away from said bar situated beneath the top and having a perforation aligning with that in said bar, a rod extending between said bar and bracket with its ends engaging said perforations and movable axially therein, a leg having a hole through which said rod passes for pivoting the leg, and a molded rubber corner comprising in-

tegral wings at right angles which extend over the outer surfaces of the frame bar to close the perforation therein.

7. A table comprising a top that includes a frame bar at the edge of the top, said bar having a horizontal perforation, a bracket spaced away from said bar situated beneath the top and having a perforation aligning with that in said bar, a rod extending between said bar and said bracket with its ends engaging said perforation and movable axially therein, a leg having a hole through which said rod passes for pivoting the leg thereto, a molded rubber corner comprising integral wings at right angles, one of which extends over and closes the perforation in the frame bar and an elastic member interposed between one side of the leg and said bar and urging the leg away from said bar.

20 In testimony whereof I hereunto affix my signature.
